(57) **CLAIM**

We claim the ornamental design for a sealable canister, as
shown and described.

DESCRIPTION

FIG. 1 is a top perspective view of a sealable container
showing our new design.

FIG. 2 is a bottom perspective view of the sealable canister
shown in FIG. 1.

FIG. 3 is a rear elevation view of the sealable canister shown
in FIG. 1.

FIG. 4 is a front elevation view of the sealable canister
shown in FIG. 1.

FIG. 5 is a right side elevation view of the sealable canister
shown in FIG. 1.

FIG. 6 is a left side elevation view of the sealable canister
shown in FIG. 1.

FIG. 7 is a top plan view of the sealable canister shown in
FIG. 1; and,

FIG. 8 is a bottom plan view of the sealable canister shown
in FIG. 1.
